S. M. PERKINS, OF MORRISON, ILLINOIS.

Letters Patent No. 64,090, dated April 23, 1867.

IMPROVEMENT IN WHIFFLE-TREE HOOKS.

The Schedule referred to in these Letters Patent and making part of the same.

TO ALL WHOM IT MAY CONCERN:

Be it known that I, S. M. PERKINS, of Morrison, in the county of Whitesides, and State of Illinois, have invented a new and useful Improvement in Whiffle-Tree Hooks; and I do hereby declare that the following is a full, clear, and exact description of the construction and operation of the same, reference being had to the accompanying drawings, made part of this specification, in which—

Figure 1 is a perspective view.

Figure 2 is a similar view of detached parts.

The object of my improvement is to remedy imperfections that have been found in practice to exist in my own whiffle-tree hook, patented November 29, 1859. In the case presented in this application this fastening is represented as applied to use as a whiffle-tree hook for securing the cockeye of a trace. I do not, however, desire to restrict its use to this particular purpose, for it is apparent that it is equally applicable to use as a button or buckle for various purposes.

A is the base, attached in the case shown to a shank which is driven into the end of the whiffle-tree. The base A is flat upon its upper face, and has a notch cut in its side, as shown at A². A¹ is a projection, having a circular shoulder at the base, and a thread cut upon its upper end. On the circular shoulder of the projecting stem A¹ is placed a washer, C, of India rubber, leather, or other suitable substance. B' is the cap through which passes the stem A, and fitted with a smooth face opposed to the corresponding face of the base A, and having a projection, B', fitting into the notch A² when the faces are in opposition. C', indicated by dotted lines in fig. 2, is a chamber formed for receiving the washer C. The chamber and washer are both round, and so arranged that the washer shall be tightly compressed in the chamber, and by the friction of the elastic washer against the sides of the chamber hold the cap from turning except by the application of a direct force for the purpose. D is a nut screwing on to the stem A, and securing the cap B in place. The cap B and base A are placed in juxtaposition when the button is to be inserted. The cockeye E is attached by first placing the oval portion of the same over the knob on the end of the hook, and then the pointed end of the hook will pass readily through the corresponding part of the cockeye. The cap being turned at right angles to the base, as shown in fig. 1, it will be impossible for the trace to become unfastened.

What I claim as my invention, and desire to secure by Letters Patent, is—

The base A, chambered cap B, and washer C, the said several parts being respectively constructed, and the whole combined and arranged for use substantially in the manner and for the purpose set forth.

In testimony whereof I have signed my name to this specification in the presence of two subscribing witnesses.

S. M. PERKINS.
